UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

COUNTING MECHANISM FOR PRINTING MACHINES.

Application filed February 12, 1921. Serial No. 444,498.

To all whom it may concern:

Be it known that I, EDWARD P. SHELDON, a citizen of the United States, residing at New York city, county of Kings, and State 5 of New York, have invented certain new and useful Improvements in Counting Mechanism for Printing Machines, fully described and represented in the following specification and the accompanying drawings, forming a part of the same.

This invention relates to certain improvements in counting mechanisms, and has been particularly designed for counting the products produced and handled in a printing 15 machine or the like.

In counting printed products in printing presses it has been heretofore customary to operate this counting mechanism from some rotary member of the machine, the counting 20 mechanism being actuated for each revolution of such member, whether or not a product was passing through or not, resulting in an incorrect count of products. Furthermore such counting mechanisms have 25 been actuated from a member located at some point of the machine prior to the actual delivery with the result that in the event of a choke or other interference with the passing of a product, the counting mechanism 30 would still be actuated, although a certain number of products would be wasted, and this wastage could not readily be calculated.

It is the especial object of the present invention to provide a simple and accurately 35 operating mechanism for counting such products in which the actuating mechanism is controlled by the product itself, so that the number of products actually delivered from a given machine may be counted and 40 wastage of paper through the machine calculated, it being known how many products of any predetermined character a given amount of paper will produce.

A further object of the invention is to 45 produce an improved mechanism for counting the products which is located at the delivery of a printing or similar machine, so that the final perfected product is counted, and no count is made for a product until it 50 has passed the delivery.

A further object of the invention is to produce an improved counting mechanism for the purposes indicated, whereby prod-

ucts forwarded in different paths may be accurately counted on separate counting 55 mechanisms or all the products counted on one mechanism.

With these and other objects not specifically referred to in view, the invention consists in certain novel parts and combinations 60 which will be described fully in connection with the accompanying drawings which illustrate a preferred form of the invention.

In the drawings:—

Figure 1 is a side view partly broken 65 away of so much of a machine for handling and delivering products as is necessary for an understanding of the invention, the products being shown delivered in two separate paths.

Figure 2 is an end or face view of part 70 of the construction shown in Fig. 1, looking in the direction of the arrow A in that figure.

Figure 3 is a sectional view of the upper 75 part of the mechanism shown in Fig. 1, the view being taken on the irregular line 3—3 of that figure.

Figure 4 is a diagrammatic view showing 80 an arrangement which may be adopted for registering on one counting mechanism the products forwarded in different paths, the parts being shown in which the counting mechanism is actuated from the upper delivery.

Figure 5 is a view similar to Fig. 4 showing the parts in the position occupied when 85 the counting mechanism is operated from the lower delivery.

Referring now to these drawings, the invention has been shown in connection with a delivery which may be part of a printing machine, though it will be understood that it may be used in other relations and with other types of mechanisms for forwarding printed products or the like which it may be desired to accurately count.

While the particular type of delivery may be varied, in the particular construction illustrated there has been shown a delivery 100 for collecting sheets and forwarding the products in different paths to the final delivery, two such final deliveries being shown.

In the construction illustrated the various parts of the machine are supported in frames 105 1 of any usual or desired construction. From

the press, not illustrated, the sheets are forwarded by forwarding rolls 2, 3 suitably mounted in the frame, to a collecting mechanism shown in the form of a cylinder 4 having three sets of grippers 5, 6 and 7 and tucking blades 8.

The collected products are delivered alternately from the collecting cylinder 4 to a pair of delivery cylinders 9, 10, provided with the usual folding jaws 11 into which the centre of the sheets is tucked by the tucking blade 8 and the sheet held on the cylinder. The products are, therefore, in the particular construction illustrated, delivered in two separate paths.

In accordance with the invention means are provided whereby these products may be accurately counted, the actuating mechanism for the counters being controlled by the products themselves. While such mechanisms may be employed at any desired point in the paths of the products to the delivery preferably such mechanism will be arranged at the final delivery so that only the perfected products actually delivered will be counted and any wastage may be accurately determined. The specific mechanism whereby the result aimed at may be accomplished may be of various characters, but where, as in the present instance, there is more than one final delivery such mechanism will be the same for each delivery employed.

In the particular construction illustrated, the delivery cylinders are provided (see Fig. 2) with grooves 12 extending around the cylinder in which work stripper fingers 13 carried on a shaft 14 mounted in the frames 1, these stripper fingers acting to strip the sheets from the cylinders. As the sheets are stripped they are delivered to any suitable device by which they are removed from the machine, as by tapes 15.

Positioned in the path of the sheets so as to be controlled thereby are devices for actuating the mechanism by which the counting of the perfected products is effected. While the specific character of these means may be somewhat varied, in the particular construction illustrated there is provided for each delivery an actuator in the form of a roll 16. This roll is carried on a stud 17 in one end of an arm 18 mounted on a rock shaft 19 extending across the machine and supported in the frames 1, before referred to. This rock shaft 19 beyond the frame 1 at one side, has fast thereon a hub 20 from which depends a rock arm 21. The arm 21 has secured thereto one end of a link 22. The other end of this link 22 is connected to a pawl arm 23 on a hub 24 carried on a stud 25 mounted in one of the side frames 1. On this hub is a ratchet 26 with which co-operates a pawl 27 pivoted on the pawl arm 23, before referred to. Also secured to

the hub 24 is a gear 28 which meshes with a similar gear 29 carried on a stud 30 suitably supported in the main frame 1. This gear 29 carries a plate 31 to the periphery of which is secured one end of a link 32, this link at its other end being connected to a rod 33 which operates a counting mechanism indicated at 34. As shown there are two of these counting mechanisms, 34, 35, one for each of the deliveries.

The actuator roll 16 is normally held in one of the grooves 12 of its delivery cylinder so as to lie in the path of the product forwarded by the cylinder. This may be easily accomplished by providing an arm 36 on the hub 20 which, as before referred to, is fast on the rock shaft 19 from which the actuator roll 16 is carried. This arm 36 is connected to a spring rod construction 37 through which the actuator roll is normally held in the groove.

In the operation of the device an advancing product marked P comes in contact with the actuator roll and lifts the roll out of the groove, as indicated in the lower delivery shown in Fig. 1. When this occurs, through the connections described the ratchet 26 is advanced a certain number of teeth, say two for instance, so that when the actuator roll has been operated ten times the ratchet will have been advanced twenty teeth, and likewise the gear 28. This causes one full rotation of the small gear 29, which has a corresponding number of teeth, say twenty. This operation of the small gear through the link 32 registers one action upon the counting mechanism, which may be arranged to indicate that ten perfected products for instance, have been delivered. It will be understood, of course, that the figures given are purely arbitrary, and that the movement and proportions of the ratchet and gears and counting mechanism may be varied as desired. This construction is, however, particularly useful with fast running machines where the products are delivered very rapidly, but the connections may be so adjusted that the passage of each product through the delivery will effect an individual action on the counting mechanism which may be used if desired with slow running machines in which the products are delivered slowly.

With the construction so far described it will be seen that an accurate count of perfect products actually delivered may be obtained, and that there is no false counting as in constructions where the revolution of a cutting cylinder or similar part is relied upon to actuate the counting mechanism, and at the same time by getting this accurate count of perfect products waste may be readily calculated.

In the construction so far described, with each delivery provided with a counting

mechanism two different styles of product may be produced upon the machine and each accurately counted.

It may be desirable in some instances 5 where the product to each delivery is the same to combine the amount of the products of both deliveries upon one or the other of the counting mechanisms. A convenient construction for effecting this is 10 shown in Figs. 4 and 5 of the drawings. In the particular construction there illustrated additional pawl arms 38 are provided on the ratchet studs 25, before referred to. These arms 38 carry pawls 39 pivoted 15 thereto and the arms are connected together by links 40. If it be desired to indicate the count of both deliveries on the counting mechanism 35, as shown in Fig. 4, the pawls 39 and 27 of the lower delivery would be 20 silenced and the pawls 39 and 27 of the upper delivery would be operated, the pawl 39 being operated through the link 40 from the lower pawl arm 23. As the products are alternately delivered by the collecting 25 cylinder to the upper and lower delivery cylinders, the upper pawls 39 and 27 would operate to register the products delivered from both deliveries on the counting mechanism 35.

30 On the other hand, if it was desired to use the counting mechanism 34, the pawls 39 and 27 of the upper delivery would be silenced and the pawls 39 and 27 of the lower delivery would be utilized to effect the count 35 from both deliveries by the counting mechanism 34.

While the invention has been shown and described in its preferred form it will be understood that various forms of devices 40 actuated by the product might be employed and that the mechanism might be located at points other than at the delivery, and in types of sheet handling and forwarding machines other than printing presses without 45 departing from the invention as defined by the appended claims.

What I claim is:

1. The combination with means for forwarding a product in different paths, of 50 counting mechanisms one for each product path, and means controlled by the products whereby all the products may be counted by one counting mechanism or the products from each path may be separately counted.
- 55 2. The combination with means for forwarding a product in different paths, of counting mechanisms, one for each product path, and means normally projecting into the paths of the products and actuated by the products for operating the counting mechanisms, whereby all the products may be counted by one counting mechanism or the products from each path may be separately counted.
- 60 65 3. The combination with a plurality of de-

liveries to which products are alternately forwarded, of counting mechanisms, one for each delivery, and means located at each delivery controlled by the products whereby all the products may be counted by one 70 counting mechanism or the products from each delivery may be separately counted.

4. The combination with a plurality of deliveries to which products are alternately forwarded, of counting mechanisms, and 75 means located at each delivery normally projecting into the paths of the products and actuated by the products for operating the counting mechanisms whereby all the products may be counted by one counting mechanism or the products from each delivery 80 may be separately counted.

5. The combination of a pair of deliveries, of a plurality of delivery cylinders, means for alternately forwarding products thereto, 85 an actuator roll co-operating with each delivery cylinder normally held in the path of a product thereon and moved by the product, counting mechanisms one for each delivery cylinder, and connections between the rolls 90 and the counting mechanism for actuating the latter whereby the products from each of the cylinders may be separately counted or all the products from the cylinders may be counted on one counting mechanism. 95

6. The combination with means for forwarding a sheet, of a collecting cylinder, a plurality of delivery cylinders to which the products are alternately delivered by the collecting cylinder, an actuator roll for each delivery cylinder normally projecting into the path of a product thereon and moved by the product, counting mechanisms one for each delivery cylinder, and connections between the rolls and the counting mechanisms 100 whereby the product from each delivery may be separately counted or all the products from the deliveries may be counted on one counting mechanism. 105

7. The combination of means for forwarding a product, of a delivery cylinder to which the product is forwarded, said cylinder having peripheral grooves, an actuator roll normally held in a groove so as to lie in the path of a product on the cylinder 115 and to be moved away from the cylinder by the product, a counting mechanism, a pawl and ratchet, connections from the roll to the ratchet, gears operated by the ratchet, and connections from the gears to the actuating mechanism for operating the latter. 120

8. The combination of a plurality of delivery cylinders, means for alternately forwarding the products thereto, an actuator roll for each cylinder normally held in the 125 path of a product on the cylinders and moved by the product, counting mechanisms one for each cylinder, connections from the roll including a pawl and ratchet for actuating the counting mechanisms, and connec-

tions whereby the rolls may actuate both ratchets to actuate each counting mechanism or whereby both rolls may operate one ratchet without actuating but one counting mechanism.

9. The combination with a plurality of delivery cylinders, of means for alternately forwarding products thereto, an actuating roll for each cylinder normally held in the path of a product on the cylinder and moved by the product, counting mechanisms one for each cylinder, a ratchet for each cylinder, a pawl for each ratchet operated from the rolls, connections from the ratchets to each counting mechanism, a second pawl for each ratchet, connections from the rolls for operating the second pawls, and means connecting the pawl operating connections so that one of the ratchets may be operated by all the rolls and the products of the cylinders counted on one counting mechanism.

10. The combination of a plurality of delivery cylinders, means for alternately forwarding products thereto, a pivoted actuator for each cylinder normally held in the path of a product thereon and moved by the product, a pawl and ratchet operated by each roll, a counting mechanism, connections

from each ratchet to a counting mechanism for actuating the counting mechanisms independently, and connections whereby the actuators operate one ratchet to cause the products from all the cylinders to be counted on one counting mechanism.

11. The combination of a delivery cylinder and means for forwarding a product thereto, a peripheral groove in the cylinder, an actuator roll working in the groove so as to lie in the path of a product on the cylinder and to be moved away from the cylinder by the product, and counting mechanism and connections from the roll for operating the counting mechanism.

12. The combination of a delivery cylinder and means for forwarding a product thereto, a peripheral groove in the cylinder, an actuator roll normally spring held in the groove so as to lie in the path of a product on the cylinder and to be moved away against the spring from the cylinder by the product, and counting mechanism and connections from the roll to the counting mechanism.

In testimony whereof I have hereunto set my hand.

EDWARD P. SHELDON.
